Term of patent 14 years

Int. Cl. D1—01

U.S. Cl. D1—13

FIG. 1 is a top plan view of a toaster pastry-snack food product showing our new design;

FIG. 2 is a side view thereof, the view from all sides being essentially the same; and

FIG. 3 is a cross-section thereof taken on line 3—3 of FIG. 1.

The bottom of the product is essentially plain.
We claim:

The ornamental design for a toaster pastry-snack food product, substantially as shown and described.
